UNITED STATES PATENT OFFICE.

JOHN G. SULTANAKI, OF SAVANNAH, GEORGIA.

TABLE-COVER.

1,332,776.

Specification of Letters Patent.

Patented Mar. 2, 1920.

Application filed January 15, 1919. Serial No. 271,250.

To all whom it may concern:

Be it known that I, JOHN G. SULTANAKI, a citizen of the United States, residing at Savannah, in the county of Chatham and 5 State of Georgia, have invented new and useful Improvements in Table-Covers, of which the following is a specification.

This invention relates to table covers and has for its object the provision of a table 10 cover which will have the general appearance of the ordinary table cover now in use but which embodies a table top covering portion of rubber or similar material which may be easily washed without removing the same 15 from the table and which therefore may be kept in a sanitary condition, the table cover as a whole including a marginal portion apron or flap which is detachably connected with the marginal portion of the top rubber section of the table cover, thereby enabling the two sections of the cover to be 20 detached from each other for the purpose of laundrying such apron or flap portion.

With the above and other objects in view 25 the invention consists in the novel construction, combination and arrangement herein fully described, illustrated and claimed.

In the accompanying drawings:—

Figure 1 is a broken plan of the table 30 cover shown in its applied position upon a table.

Fig. 2 is a side elevation of the same.

Fig. 3 is an enlarged fragmentary vertical section through the same.

85 The improved table cover contemplated in this invention comprises a main table top cover section 1 and a detachable section 2 which corresponds with the skirt or apron or flap portion of the ordinary table cover 40 now in common use, the portion 2 being adapted to hang pendent from the edge of the table as shown in the drawing.

The section 1 of the table cover is formed of rubber or rubberized fabric, oil cloth or 45 any like sheet material and the dimensions thereof correspond substantially with the dimensions of the top of the table.

The marginal portions 2 of the table cover may be composed of any suitable 50 tile material such as that now used in the

manufacture of table covers or cloths. The sections 1 and 2 of the table cover are connected detachably together by fastening means shown as consisting of the ordinary snap fasteners such as are used for glove 55 fasteners. In order to apply the fasteners to the sections 1 and 2, it is preferred to secure the stud members 3 to the section 1 of the table cover by turning in the marginal portion of the section 1 and forming a hem 60 4 and inserting the fastening members 3 through the inner ply of said hem as clearly shown in Fig. 3, the head of the stud 3 projecting beyond the inner surface of said inner ply of the hem 4. The other socket 65 member 5 of the fastener is secured to the table cover section 2 the upper edge of which is preferably folded over and outwardly as shown in Fig. 2 and the fastening member 5 being inserted in the inner ply of such 70 folded portion and secured in place in any suitable or usual manner.

From the foregoing description taken in connection with the accompanying drawing it will now be seen that the table cover sections may be readily separated from each other in order to enable the section 2 of the table cover to be laundried. The section 1 of the table cover may be thoroughly cleaned and kept in a sanitary condition by 75 washing or rubbing the same with a damp cloth while in its position upon the table top. This will save considerable laundrying and require a less number of table cloths to be carried in eating places, hotels, restaurants and the like.

I claim:—

A table cover comprising a main table top covering section of rubber sheeting having a marginal portion thereof turned inwardly and hemmed, a pendent flap or skirt section having its upper marginal portion turned outwardly and downwardly, and snap fastening members secured to the inner adjacent plies of the table cover sections whereby said sections are detachably connected in operative relation.

In testimony whereof I affix my signature.

JOHN G. SULTANAKI.
